UNITED STATES PATENT OFFICE.

PASQUALE PENZA, OF BOLOGNA, ITALY.

PNEUMATIC-DYNAMIC CAR FOR DIMINISHING THE DESTRUCTIVE EFFECTS OF RAIL-ROAD COLLISIONS.

1,218,310.

Specification of Letters Patent.

Patented Mar. 6, 1917.

Application filed December 4, 1914. Serial No. 875,417.

To all whom it may concern:

Be it known that I, PASQUALE PENZA, subject of the King of Italy, residing at Bologna, Italy, have invented certain new and useful Improvements in Pneumatic-Dynamic Cars for Diminishing the Destructive Effects of Railroad Collisions, of which the following is a specification.

The object of this invention is to absorb the momentum of a moving railway train in the case of such train colliding with another train, or other obstacle, so as to diminish the destructive effects of the collision with respect to passengers, goods, and rolling stock.

This object is attained, according to the present invention, by the provision of a tank containing compressed air such tank, when a collision occurs, being reduced in its volume to increase the compression of the air and by this increased pressure special valves automatically open allowing a gradual continuous outflow of the compressed air into the atmosphere. By these means the momentum of the moving train will only produce a compression of the air in the tank. Means are also provided to admit the compressed air to the main air brake pipe so as to automatically actuate the air brakes.

Such a car is preferably placed in the front part of the train, that is to say, just behind the locomotive tender and at the end of the train.

A constructional example of the invention is illustrated in the accompanying drawings, in which:—

Figure 1 is a partial longitudinal section and a partial elevation of the car. Fig. 2 is a plan view of one half of the car.

Fig. 3 is a cross section of the car taken on the line A—A Fig. 1.

Figs. 4 and 5 are details of constructions hereinafter referred to.

The dimensions of the improved car may vary between a maximum, as represented for instance by a sleeping car and a minimum as represented for instance by a common small freight car according to the strains to be taken up by the air cushion and in accordance with traffic rules and regulations regarding railway rolling stock.

The improved car comprises two ordinary car frames 1—1 made of heavy steel beams such frames being mounted upon the trucks 55 2—2 with double or single axles. Upon the

frame are erected the car bodies 3—3, very strongly made of iron or steel plates. The car bodies 3—3 are slidably connected by a system of beams 4 arranged on the top and on the sides of the car. These beams are 60 connected at their central part by means of bolts to a metal band 5 situated in a vertical plane, such metal band being employed in order to create a solid fastening of the beams between each other. The beams are 65 supported with their ends within guides or pockets 22 formed by a bent iron sheet which is fastened on the walls of the car body. These guides are provided on the top wall and on the side walls of the car bodies 70 and made so as to allow the system of beams 4 to slide therethrough. Cuts 23 are provided in the lower guides 22 and projections 24 carried by the corresponding beams engage said cuts so that the beams 4 cannot be 75 drawn entirely out of the car bodies. Between the car bodies a double system of tubes of iron 6 constituting an air tank is provided in such a manner that the different tubes allow a telescopic movement between each other while a perfectly tight joint is maintained between the several tubes. The central element of this telescopic air tank is suspended by the metal band 5 by means of vertically adjustable hook 7 and 80 85 the outside ends of the telescopic air tank are fastened to the inner walls of the car bodies 3—3.

In Figs. 4 and 5 are represented two devices for rendering the elements forming 90 the air tank perfectly airtight.

In Fig. 4, 8 is a leather or rubber ring kept against the wall of the cylinder by a metallic ring 9 having an annular groove in which is supported the circular spring 10. 95 Bolts 11 connect the leather ring 8 to the metallic ring 9 and the whole to the flange of the tubing 6. The spring 10 insures the continuous adherence of the packing to the inside wall of the cylinder and therefore a 100 perfect tightness during the displacement of one cylinder within the other is obtained.

In Fig. 5, another device is shown for rendering the elements forming the air tank perfectly air-tight. In this case a gummed 105 woven material 12 is applied against the wall of each of the iron tubes 6 of the tank, such material assuming a corrugated shape when in compressed condition. The edges of the woven material are overlapped be- 110

neath the edges of the tubing and these overlapped portions are kept against the wall of the tubing by means of wooden rings 13 each bearing a rubber packing 14 on its circumference. Threaded bolts 16 screwing into a common central nut 15 (see Fig. 3) are provided to keep the packing 14 against the wall of the tank and to insure the necessary tightness.

10 If desired both of the devices shown in Figs. 4 and 5 may be applied to the tubes in case practical requirements need this.

The air tank is fitted with two kinds of valves, the first kind, serving for the admission of air from the tank into the main pipe 19 of the air brake, being conveniently located in the lugs 17 forming an extension of the air conduit 18. The other kind 20 allow the outflow of air from the tank into the atmosphere after a collision. The discharge valves 20 are of large cross sectional opening and provided with spiral springs 21 of different strength in order to establish in the different discharge valves different resistances for the outlet of the air according to practical requirements.

From the foregoing it will be understood that the improved car, in case of a collision, will act as a very powerful cushion while at the same time the valves in connection with the main pipe of the air brake will be opened and an immediate braking of the train will be caused, independently of the engine driver.

35 If all the air contained in the air tank should become expelled, there will still remain a very resistant cushion consisting of the two end parts of the car, which parts with their boxes may serve very well for the 40 transportation of luggage, goods, mail and so on. In case of a breakdown in the working of the air pump, the air tank may be used to feed the air brake pipe until the necessary repairs have been made.

45 What I claim is:—

1. A car for absorbing shocks caused by a collision or the like comprising two rela-

tively movable end car bodies, an air tank acting as an air cushion and composed of a double system of telescopic tubes the ends 50 of which are connected to said car bodies, wheel trucks upon which said car bodies are mounted, beams surrounding the air tank, guides formed in the walls of the car bodies to receive the ends of said beams and means 55 for controlling, in case of a collision, the escape of air from the air tank to the atmosphere.

2. A car for absorbing shocks caused by a collision or the like comprising two relatively movable end car bodies, wheel trucks upon which said car bodies are mounted, an air tank comprising a system of telescopic tubes the ends of which are connected to said car bodies, beams surrounding the air tank 65 and slidingly engaging the walls of the said car bodies, valves for permitting, in the event of a collision, the escape of the air compressed in said air tank to the atmosphere at a desired pressure, an air brake 70 pipe and means for also permitting compressed air to pass from the air tank to said brake pipe.

3. A car for absorbing shocks caused by a collision or the like comprising two relatively movable end car bodies, wheel trucks upon which said car bodies are mounted, an air tank comprising a system of telescopic tubes the ends of which are connected to said car bodies, a lining of flexible material 80 arranged within said tubes to render them airtight, means for maintaining said lining in position, beams surrounding the air tank and slidingly engaging the walls of the said car bodies, valves for permitting, in the event of a collision, the escape of the air compressed in said air tank to the atmosphere at a desired pressure, an air brake 85 pipe, and means for also permitting compressed air to pass from the air tank to said 90 brake pipe.

In testimony whereof I have affixed my signature.

PASQUALE PENZA.
